UNITED STATES PATENT OFFICE.

JOSIAH KING HUTCHINSON, OF BEAVER, AND ROBERT HENRY WALLACE, OF NEW BRIGHTON, PENNSYLVANIA.

SPIKE OR NAIL.

1,031,556.

Specification of Letters Patent. Patented July 2, 1912.

Application filed August 26, 1911. Serial No. 646,241.

To all whom it may concern:

Be it known that we, JOSIAH KING HUTCHINSON, a resident of Beaver, in the county of Beaver and State of Pennsylvania, and ROBERT HENRY WALLACE, of New Brighton, in said county and State, have invented a new and useful Improvement in Spikes or Nails; and we do hereby declare the following to be a full, clear, and exact description thereof.

10 Our invention relates to a spike or nail which acts as a sod stay and has for its special object a means of holding sods upon sloping or inclined surfaces to prevent them from slipping out of place after a shower of

15 rain or when walked upon.

The object of our invention is to provide a cheap, simple and efficient form of spike, nail sod holder or stay which can be formed from a single piece of metal and will be

20 quickly and easily formed, and may be used at any angle or on any incline to prevent the sods from slipping out of place.

To these ends our invention consists in the novel form of spike or nail as herein-
25 after more specifically set forth and de-
scribed, and particularly pointed out in the
claims.

To enable others skilled in the art to which our invention appertains to make and use
30 our improved spike or nail we will describe the same more fully referring to the accom-
panying drawing in which:

Figure 1 is a front elevation of our im-
proved spike or nail. Fig. 2 is a top plan
35 view of the same. Fig. 3 is a cross sectional
view on the line 3—3 Fig. 1 looking in the
direction of the arrows. Fig. 4 is a side elev-
ation of the same partly broken away.

Like symbols of reference herein indicate
40 like parts in each of the figures of the
drawing.

As illustrated in the drawing A represents our improved spike or nail which is formed of any suitable material, such as steel, brass,
45 etc., and has an upright spike or shank portion 1 which tapers at its lower end to a sharp or flat point 2 and said spiked portion is curved at its upper end at a 90° angle so that the top thereof forms an overhang-
50 ing head portion 3 thereon. The overhang-
ing portion 3 extends out from the spiked portion 1, a suitable distance and is provided with a lug or flange extending out from each side of said overhanging portion to form a

T head or securing portion 4 as shown in 55
Figs. 2 and 3.

The sods are placed side by side in the usual manner in order to cover the place desired and their edges are placed close together to present the appearance of a grassy bank. It is very usual for the sods so placed to become spread apart by persons walking over the same, or by the water from a recent rain soaking down between the same and causing the sods to slide apart. In cases 65 where the sods are placed on an incline or slope they are very apt to spread apart and slide after a light rain and thus spoil the appearance of the sodded bank or slope and require resodding to repair the damage. After 70 the sods are laid and placed in the position desired, the spike or nail A is driven down through the same in any convenient part thereof and such stay passes entirely through said sod by its sharp or flat point 2 and 75 enters the ground beneath such sod, the said point enabling such stay to be easily driven into the ground, while the spike portion 1 and overhanging portion 3 are of such firmness as to permit hammering upon said 80 overhanging portion to drive the point 2 into the ground without injuring the shape of the same or bending it in any manner. The spike or nail A is hammered into the ground until the securing portion 4 rests 85 firmly against the top of the sod and holds it securely against the ground.

It is well known that it is practically impossible to lay sods upon an incline or slope with any degree of certainty as to their remaining in the position placed in, and even if stakes or spikes are used the sod on expanding after a shower of rain will raise itself above said stake or spike and slip down over the same, unless such stake is of 90 an unusual height which is very undesirous on account of the appearance of the grassy slope.

With the use of our improved spike or nail the sod may be securely fastened to the 100 ground as described and when so fastened will not be noticeable in any way, while rain or water will not cause the same to leave its position nor will the sod be pushed from place by a person walking upon the same, 105 all of which has been proven from practical experiments with said spike or nail.

The spikes or nails may be placed at fre-

quent intervals throughout the area of the sod and may be removed after the sod has become rooted to the natural soil or may be left where driven.

5 It will be evident that our improved spike or nail may be used for purposes other than holding sods and various modifications and changes in the form and design of our improved spike or nail may be resorted to within the scope of the claims without departing from the spirit of the invention or sacrificing any of its advantages.

What we claim as our invention and desire to secure by Letters Patent is:—

10 15 1. A spike or nail comprising a shank having a head substantially at a right angle thereto, said head being provided with outwardly extending portions on the sides of the same at a distance from said shank.

2. A spike or nail comprising a shank 20 having a head substantially at a right angle thereto, said head being provided with outwardly extending portions on the sides of the same at the end thereof.

3. A spike or nail comprising a shank 25 having a head substantially at a right angle thereto, said head being provided with outwardly extending portions on the sides of the same and at the outer extremity of the same.

30 In testimony whereof, we the said JOSIAH KING HUTCHINSON and ROBERT HENRY WALLACE have hereunto set our hands.

JOSIAH KING HUTCHINSON.
ROBERT HENRY WALLACE.
